To all whom it may concern:

Be it known that I, CLARENDON HERBERT THORP, a citizen of the United States, residing at Alexandria, in the county of Licking and State of Ohio, have produced a new and original Design for a Halter-Buckle, of which the following is a specification.

The design is characterized by an inverted triangular loop 1, connected to a circular eye

2 by an intermediate neck 3, having concave 15 sides 4. The corners 5 of the loop 1 are curved.
